UNITED STATES PATENT OFFICE.

ARTHUR TREVOR DAWSON AND GEORGE THOMAS BUCKHAM, OF WESTMINSTER,
LONDON, ENGLAND, ASSIGNORS TO VICKERS LIMITED, OF WESTMINSTER,
LONDON, ENGLAND.

ORDNANCE.

1,302,519.

Specification of Letters Patent.

Patented May 6, 1919.

Application filed April 13, 1915. Serial No. 21,123.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Ordnance, of which the following is a specification.

This invention relates to ordnance of the kind working on the semi-automatic principle in which the empty cartridge case is automatically extracted and ejected from the breech chamber during the run out movement of the gun after recoil. The ejection of the case is at times so violent that it is liable to become damaged or to damage parts of the mounting and also to injure any of the gun's crew in the vicinity, more especially when the case falls a comparatively great distance such as may occur when the gun is on a mounting in which the magazine is situated a considerable distance beneath the gun and when the latter is of large caliber and the cartridge case consequently heavy.

According to this invention we provide a movable stop device which is so constructed and arranged that during ejection the cartridge case will come into contact therewith and thus be prevented from becoming completely ejected from the breech chamber. The said device can then be displaced into a position to enable the case to be removed by hand. Suitable means are provided for automatically moving the stop device into its inoperative position to enable the loading operation to be performed.

In order that the said invention may be clearly understood and readily carried into effect, we will describe the same more fully with reference to the accompanying drawings, in which:—

Figure 1 is a sectional plan showing a constructional form of the stop device in position on the gun.

Figs. 2 and 3 are rear elevations illustrating the stop device used in conjunction with a loading tray carried by a hoist, Fig. 2 showing the stop device displaced to enable the gun to be loaded and Fig. 3 showing this device in its operative position.

Figs. 4 and 5 are respectively a sectional plan and a rear elevation showing the stop device on a larger scale.

A is the breech end of the gun. B represents the movable stop device which in the example shown is hinged on a longitudinal pivot b carried by a bracket B' extending rearwardly from the gun cradle. The forward portion of the stop device carries a buffer b' controlled by a spring or otherwise which absorbs the shock of impact of the cartridge case; the said device is provided with a handle B^2 by means of which it can be shifted into the position shown by chain lines in Fig. 5, to enable the cartridge case to be completely removed from the gun. The stop device is so arranged that its weight causes it to assume its operative position (Fig. 3) or it may be spring controlled so that it normally assumes this position. The said stop device may have two projections b^2, b^3 which coöperate with a fixed stop b^4 to limit the movements of the device into its operative and inoperative positions.

The stop device is adapted to be displaced automatically to its inoperative position for enabling the loading operation to be performed, by the movement of the loading tray into its loading position behind the gun. For example when the gun is on a mounting in which the ammunition is as shown raised in a hoist B^3 from the magazine, a bracket B^4 is formed on the loading tray or other suitable portion of the hoist for lifting the stop device into the inoperative position, shown in Fig. 2, to enable the loading operation to be performed.

What we claim and desire to secure by Letters Patent of the United States is:—

1. The combination with a breech loading gun, of means for preventing the used cartridge case from becoming completely ejected from the breech chamber during the opening of the breech the cartridge case remaining partly within the breech chamber when the gun reaches its run-out position, and having to be removed by hand from this chamber.

2. The combination with a breech loading gun, of a stop for preventing the used cartridge case from becoming completely ejected from the breech chamber during the opening of the breech and of means whereby said

stop can be displaced by hand for permitting the removal of the partially ejected cartridge case from the breech chamber when the gun reaches its run-out position.

5. 3. The combination with a breech loading gun, of a hinged arm, and a buffer carried by said arm for preventing the used cartridge case from becoming completely ejected from the breech chamber, during the 10 opening of the breech and of means whereby said arm can be displaced for permitting the removal of the partially ejected cartridge case.

4. The combination with a breech loading 15 gun, of a hinged arm, a buffer carried by said arm for preventing the used cartridge case from becoming completely ejected from the breech chamber during the opening of the breech and means for permitting move-

ment of said arm within certain limits to 20 enable the cartridge case to be removed.

5. In breech loading ordnance, the combination of a movable stop for preventing the used cartridge case from becoming completely ejected from the breech chamber during the 25 opening of the breech, an ammunition hoist, and means thereon for moving said stop to its inoperative position as the hoist reaches its loading position, to enable the cartridge case to be removed.

30 In testimony whereof we affix our signatures in the presence of two witnesses.

ARTHUR TREVOR DAWSON.
GEORGE THOMAS BUCKHAM.
